PIVOTAL MOUNTING FOR HORIZONTAL CUTTER BAR AND DRIVE MEANS FOR THE CHAIN SUPPORTED THEREBY

Leon E. Simmons, deceased, late of Claremont, N. H., by Gladys L. Simmons, administratrix, Claremont, N. H., assignor to Joy Manufacturing Company, Pittsburgh, Pa., a corporation of Pennsylvania

Original application October 16, 1948, Serial No. 54,895, now Patent No. 2,657,915, dated November 3, 1953. Divided and this application October 24, 1951, Serial No. 252,846

3 Claims. (Cl. 262—30)

This invention relates to mining machines and more particularly to the kerf cutting mechanism of a coal mining machine of the pivoted cutter bar, longwall type.

An object of the present invention is to provide an improved kerf cutting mechanism. Another object is to provide an improved coal mining machine of the pivoted bar, longwall type having an improved pivotal mounting structure for the cutter bar and improved driving means for the cutter chain. These and other objects and advantages of the invention will, however, hereinafter more fully appear.

This application is a division of a copending application, Serial Number 54,895, filed October 16, 1948, and since issued as Patent No. 2,657,915, owned by the same assignee as the present invention.

In the accompanying drawing there is shown for purposes of illustration one form which the invention may assume in practice.

In this drawing:

Fig. 1 is a plan view, with parts broken away, of a longwall coal mining machine in which an illustrative embodiment of the invention is incorporated.

Fig. 2 is an enlarged vertical section taken on the planes of line 2—2 of Fig. 1, showing details of the kerf cutting mechanism.

Fig. 3 is a detail horizontal section taken on line 3—3 of Fig. 2.

Fig. 4 is a fragmentary vertical section showing the releasable interlock between the ring-flange and shaft-groove.

The coal mining machine in which the invention is embodied is generally designated 1 and, as disclosed in the earlier filed application, Serial No. 54,895 above referred to, generally comprises a vertically compact machine frame 2 slidable on its bottom 3 for movement over the floor of a mine, and carrying at its rear end a kerf cutting mechanism 4 and at its front end a flexible feeding mechanism 5; said cutting and feeding mechanisms being driven by a motor 6 arranged centrally on the frame between the cutting and feeding mechanism as shown in Fig. 1. While the invention is shown embodied in a longwall type coal mining machine, it will be evident that the same may be embodied in coal mining machines of other types.

The machine frame 2 comprises a rear cutter frame section 7, a front feed frame section 8 and a central motor frame section 9 and these sections are suitably rigidly united to provide a low compact frame unit structure slidable over the mine floor. Pivotaly mounted on the cutter frame section 7 on an upright axis at 10 is a horizontal plane cutter bar or jib 11 having a conventional cutter bit or pick carrying cutter chain 12 guided for orbital circulation about its margin. Carried by the feed frame section 8 is a horizontal feed drum 13 on which a feed cable 14 is wound and this cable may be extended from the feed drum into connection with the cutter bar for effecting swinging of the latter about its pivot or in advance of the machine to a suitable anchor jack to effect bodily feeding of the machine in an endwise direction along the coal face, all as is fully disclosed in the above mentioned copending application.

Now referring to the detail structure of the kerf cut-

ting mechanism 4, it will be noted that driven by the motor shaft 17 (Fig. 1) is a bevel pinion 18 which meshes with and drives a large horizontal bevel gear 19 (Fig. 2) which has its hub keyed at 19' to a vertical tubular shaft 20. The shaft 20 is journaled at its upper end on an anti-friction bearing herein desirably a roller bearing 21 supported by a detachable top cover plate 22 of the cutter frame, and is journaled intermediate its ends, near its middle portion, on an anti-friction bearing likewise desirably a roller bearing 23 supported by a circular bearing support or bearing annulus 24 formed integral with the cutter frame section and arranged coaxial with the shaft 20, and the cutter bar or jib 11 is pivotally mounted on this bearing support as hereinabove explained. A cap 25, detachably secured as by screws to the cover plate 22, has an integral shaft 26 welded thereto at 27 and this plate-shaft extends centrally through the tubular shaft 20 and is threadedly attached at 28 within a threaded boss integral with the detachable lower frame portion or bottom plate 29 of the cutter frame. The shaft 26 rigidly ties the superimposed top and bottom plates of the cutter frame section together. Keyed at 29' to the lower portion of the shaft 20 is a conventional chain sprocket 30 having a hub 30' and this sprocket engages and drives the endless cutter chain 12. The lower end of the shaft 20 is annularly grooved at 31 and a split ring or plate 32, secured as by screws to the sprocket hub 30', has a flange 33 fitting in this groove to hold the sprocket against displacement axially of the shaft. The upper end of the shaft 20 is annularly grooved to receive a conventional split ring 34 which engages the upper surface of the inner race of the upper roller bearing 21. The lower end of the hub of the bevel gear 19 and the upper end of the sprocket hub abut the opposed end surfaces of the inner race of the lower roller bearing 23, as shown in Fig. 2. A dirt seal 35 carried in a recess in the upper portion of the tubular shaft 20 sealingly engages the inner shaft 26 to prevent access of dirt to the upper roller bearing 21. The bearing support 24 carries a similar dirt seal 36 which sealingly engages the sprocket hub to prevent access of dirt to the lower roller bearing 23 and to prevent leakage of lubricant from an upper frame chamber 37 in which the bevel gears are arranged. This chamber has an upper wall provided by the cover plate 22 and a lower wall 37'. In this improved construction, the bearing support or annulus 24 supports bearing elements or sleeves 38 (Fig. 2) on which a hub 39 of a hanger frame 40 is swiveled, and the cutter bar 11 is secured as by screws 40' to and supported by this hanger frame to swing horizontally about the vertical axis 10 relative to the machine frame. An annular retaining plate 41 is secured as by screws 41' to the bottom of the bearing annulus 24 for retaining the hub of the hanger frame in position on its bearings. The hanger frame has an upstanding boss 42 grooved at 43 to receive an arcuate guiding flange 44 on the cutter frame. A rotary locking pin 45 is arranged in a bore in the boss 42 and is grooved at 46 to receive the guide flange 44 and has a circular body portion which, upon rotation of the pin, is receivable in any one of three spaced notches 47 in the guide flange 44 for rigidly locking the cutter bar in its different positions to the machine frame. The rotary locking pin and grooved boss structure does not per se enter into the present invention and is fully disclosed in the copending application above referred to. The feed cable 14 is attachable to this locking pin for effecting swinging of the cutter bar 11 on its swivel mounting. From the foregoing, it will be evident that when the motor is running the cutter chain 12 may be rapidly circulated about the margin of the cutter bar 11 through the bevel gearing 18, 19, the vertical shaft 20 and the chain drive sprocket 30. As disclosed in the above mentioned copending application, a releasable clutch is arranged between the motor shaft and the bevel pinion 18 so that the cutter chain may remain idle during running of the machine motor. Since the manner of use of the mining machine is fully disclosed in the above mentioned copending application further description thereof is herein unnecessary.

As a result of this invention an improved kerf cutting mechanism is provided especially designed for use with a pivoted bar, longwall type coal mining machine having novel pivotal mounting means for the cutter bar and improved driving means for the cutter chain. The improved shaft structure coaxial with the bar pivot provides an extremely rigid reinforcing means for the cutter frame and the improved relation of the cutter chain driving means with this coaxial shaft results in a structure which is extremely vertically compact. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What is claimed as new and desired to secure by Letters Patent is:

1. In a mining machine a frame having an upper frame portion providing a horizontal chamber having parallel upper and lower walls, and a parallel lower floor engaging portion, said lower wall of said chamber having a depending circular bearing supporting portion, a horizontal cutter bar projecting laterally from said frame and having its inner portion arranged between said upper and lower frame portions, a hanger frame swivelly mounted on and entirely swivelly supported by said circular bearing supporting portion, said cutter bar having an endless cutter chain guided thereon for orbital circulation, a driving gear arranged in said chamber, a vertical tubular drive shaft secured at its upper portion to and driven by said gear, bearings respectively supported by said upper wall and said circular bearing supporting portion and spaced axially of said shaft for journaling the latter for rotation, said shaft supporting said gear and having its lower end portion extending freely downwardly axially through said circular bearing supporting portion below the latter without contact with said lower frame portion, a chain sprocket secured to the lower free end portion of said shaft for driving said cutter chain, said sprocket being supported entirely by said shaft below said circular bearing portion and spaced above said lower frame portion, a rigid tie shaft secured at its ends to said upper wall of said upper frame portion and to said lower frame portion and extending axially through said tubular shaft, and a detachable retaining plate secured to the bottom of said circular bearing supporting portion for retaining said hanger frame in swivelly supported position on said circular bearing supporting portion, said chain sprocket having a hub and said retaining plate surrounding the upper portion of said hub.

2. In a mining machine, a frame having an upper frame portion providing a horizontal chamber having parallel upper and lower walls, and a parallel lower floor engaging portion, said lower wall of said chamber having a depending circular bearing supporting portion, a horizontal cutter bar projecting laterally from said frame and having its inner portion arranged between said upper and lower frame portions, a hanger frame swivelly mounted on and entirely swivelly supported by

said circular bearing supporting portion, said cutter bar having an endless cutter chain guided thereon for orbital circulation, a driving gear arranged in said chamber, a vertical tubular drive shaft secured at its upper portion to and driven by said gear, said device shaft having an annular groove on the lower portion thereof, bearings respectively supported by said upper wall and said circular bearing supporting portion and spaced axially of said shaft for journaling the latter for rotation, said shaft supporting said gear and having its lower end portion extending freely downwardly axially through said circular bearing supporting portion below the latter without contact with said lower frame portion, a chain sprocket secured to the lower free end portion of said shaft for driving said cutter chain, said sprocket being supported entirely by said shaft below said circular bearing portion and spaced above said lower frame portion, a rigid tie shaft secured at its ends to said upper wall of said upper frame portion and to said lower frame portion and extending axially through said tubular shaft, and a detachable circular retaining plate received at its inner peripheral portion within said annular groove on the lower portion of said tubular drive shaft and secured to said sprocket for retaining said sprocket against downward axial displacement from the free lower end of said drive shaft.

3. In a mining machine, the combination comprising a frame having parallel horizontal top and bottom frame portions, a rigid tie shaft extending vertically between said frame portions and rigidly secured thereto for tying said frame portions together, said frame having an intermediate parallel frame portion spaced from said top frame portion and having a depending annular bearing supporting portion, a hanger frame swivelly mounted on said bearing supporting portion to swing in horizontal planes relative thereto, a horizontal plane cutter bar carried by said hanger frame, an endless cutter chain guided for orbital circulation about the margin of said cutter bar, driving means for said cutter chain comprising a vertical tubular drive shaft coaxial with and surrounding said tie-shaft and having a depending free lower portion extending downwardly through and below the bottom of said bearing supporting portion, a driving gear secured to the upper portion of said drive shaft and arranged in the space between said top frame portion and said intermediate frame portion and a cutter chain drive sprocket secured to the lower portion of said drive shaft below said intermediate frame and bearing supporting portions, detachable retaining means secured to said depending bearing supporting portion for holding said hanger frame in position on said depending bearing supporting portion, and detachable retaining means secured to said sprocket and interlocked with said drive shaft for retaining said sprocket in position on said drive shaft against downward displacement axially of the latter.
